UNITED STATES PATENT OFFICE.

HENRY W. COMSTOCK, OF BOSTON, MASSACHUSETTS.

DESIGN FOR A TOBACCO-PIPE.

SPECIFICATION forming part of Design No. 35,637, dated January 28, 1902.

Application filed December 18, 1901. Serial No. 86,459. Term of patent 8½ years.

To all whom it may concern:

Be it known that I, HENRY W. COMSTOCK, a citizen of the United States, residing at Boston, in the county of Suffolk and State of Massachusetts, have invented and produced a new and original Design for Tobacco-Pipes; and I do hereby declare the following to be a full, clear, and exact description of the same, reference being had to the accompanying drawing, forming a part thereof.

In the drawing is represented a side elevation of a tobacco-pipe, showing my new design.

In the said drawing, A is the bowl of the pipe, and B is the stem or mouthpiece. X X show the center or axial line of said bowl, and Y Y show the center or axial line of the stem or mouthpiece.

The leading or material feature of my design consists in making the pipe with the axial lines of the bowl and mouthpiece or stem substantially in parallel planes, the outer contour connecting said stem and bowl being made ogee or of a reverse curve, as represented in the drawing.

Having described my invention, what I claim as new, and desire to secure by Letters Patent, is—

The design for a tobacco-pipe as herein shown and described.

In testimony whereof I have affixed my signature in presence of two witnesses.

HENRY W. COMSTOCK.
